UNITED STATES PATENT OFFICE.

AUBREY J. GRINDLE, OF CHICAGO, ILLINOIS, ASSIGNOR TO GRINDLE FUEL EQUIPMENT COMPANY, OF HARVEY, ILLINOIS, A CORPORATION OF ILLINOIS.

PULVERIZER.

Application filed July 17, 1926. Serial No. 123,239.

This invention relates to a machine for pulverizing various materials. For the purposes of illustration and not by way of limitation, the invention is described as a mechanism for pulverizing coal but it is to be understood that it may be equally used for the pulverization of any suitable material.

In breaking up relatively coarse fuel by the use of moving, usually rotating, breakers or beaters, a relatively low speed for such mechanism is most satisfactory for the initial disintegration of the fuel to particles of, say, a quarter of an inch in diameter; but subsequent similar treatments of the fuel, reducing its particles to successively smaller and smaller sizes, require successively increased speeds of the breaker or beating devices to efficiently produce the final powdered fuel of ultimately desired fineness.

The object of this invention is to provide a single machine, preferably one rotating about a vertical axis, equipped with a plurality of breaking or beating wheels of progressively increased diameter and consequently correspondingly increased circumferential speeds to which the fuel to be disintegrated or pulverized may be passed in a single operation to secure the desired result with maximum efficiency as to power required, space occupied by the machine and manual attendance. The invention further consists in a novel mounting for the wheel; novel means of feeding the wheel and novel breakers carried by the wheel. The invention consists in mechanism capable of attaining the foregoing and other objects; which can be easily and cheaply made; which is satisfactory in use and is not readily liable to get out of order.

More particularly the invention consists in numerous features and details of construction which will be hereafter more fully set forth in the specification and claims.

Referring to the drawings in which like numerals designate the same parts throughout the several views:

Figure 1 is a side elevation of mechanism illustrating this invention in its preferred form.

Figure 2 is a plan view, certain parts being shown in section, on the irregular line 2-2 of Figure 1.

Figure 3 is a sectional, plan view on the line 3-3 of Figure 1.

Figure 4 is a central sectional side view on the slightly irregular line 4-4 of Figure 2.

Figure 5 is an enlarged, detailed view of the pump appearing at the bottom of the centre of Figure 4.

Figure 6 is a detailed plan view on the line 6-6 of Figure 5.

Figure 7 is a detailed plan view on the irregular line 7-7 of Figure 4.

The subject matter of the foregoing figures was shown, described and claimed in an earlier application, Serial Number 1194, filed January 8, 1925, and abandoned at the instant of the filing of this application, which incorporates the same subject matter.

Figure 8 is a modified form of wheel construction designed to support beaters which are an improvement upon corresponding devices 98 of the earlier figures.

Figure 9 is a plan view on the line 9-9 of Fig. 8.

Figure 10 is an enlarged plan, detail view of a beater.

Figure 11 is a sectional, side view through Figure 10, showing the mounting of the beater.

The essential parts of the invention are directly or indirectly sustained by a hollow, centrally apertured case or table 10, detachably secured by bolts 12 to a multiplicity of legs 14 resting on the floor 16 or the like.

Closing the center aperture of the case and held in place by the bolts 18 is a horizontal flange 20 of a vertically disposed tubular case 22, within which is rotatably mounted vertical shaft 24, turning in upper bushing 26 and lower bushing 28 mounted in said case. The upper end of tubular case 22 is closed by a shaft enclosing cap 30, detachably held in place by any suitable means, as screws 32. Rigidly secured to shaft 24 between cap 30 and the upper end of bushing 26 is a downwardly cupped disc 34, having a down-turned outer edge which serves to keep oil in position to enter and travel down four grooves 35 on the outside of bearing 26. Shaft 24 is, near its bottom, provided with a shoulder 36 resting upon an anti-friction mechanism 38 carried by a plug 40 fastened by means of screw threads 42 into the lower end of tubular case 22. This plug 40 is provided with a multiplicity of oil passages 44 entering an oil reservoir

46 detachably secured in place by bolts 48.

passing through flange 50 on the bottom of tubular case 22. This oil reservoir 46 has in its bottom a central perforation 52 through which the extreme lower end portion 54 of shaft 24 enters the bearing 56 upon the lower side of oil pump case 58, detachably secured by screws or bolts 60 to the lower side of oil reservoir 46. Rigidly mounted on shaft portion 54 by any suitable means, 10 as, for instance, key 62 and rotatable inside of oil pump case 58 is a conventional pump wheel 64 adapted as shaft 24 is rotated to drive oil from oil reservoir 46, descending through passage 52 out through pipe mechanism 66 to T 68 through which it flows via pipe 70 to the interior of bushing 26 and via pipe 71 to the interior of bushing 28, thereby effectively lubricating all essential parts of shaft 24. The oil from bushing 26 15 turns to oil reservoir 46 through the interior of case 22 and by-pass 72. The oil from bushing 28 returns to oil reservoir 46 through oil passages 44.

The mechanism just described affords a 20 self-contained, continuously operating oiling device for the shaft 24, which insures its proper operation and the consequent proper operation of the remainder of the machine to be hereafter described, notwithstanding 25 the continuous presence of finely powdered fuel in which the machine of this invention is forced to continuously operate.

Rigidly secured to shaft 24 above cap 30, in the particular case here illustrated, integral therewith, is a flange 74 sustaining the inverted U-shaped hub 76, rigidly secured in place by any suitable means as, for instance, studs 78. The lower end of this hub 76 is provided with an outwardly extending flange 80, carrying a downwardly extending cone 82 from which project air driving wings 84 rotatable inside of the top interior recess 86 of the table or case 10 below cover plate 85, having an annular perforation 87 of less external diameter than wheel 90 hereafter referred to. Tightly enclosing hub 76, secured in place by a multiplicity of bolts 88 are a plurality of fuel material disintegrating wheels 90-91-92-93 and 94, spaced apart 30 by suitable washers 96. Each of these wheels is provided with a multiplicity of circumferentially disposed beaters 98 projecting sufficiently from the circumference of the respective wheels to operatively cooperate with 35 the interior teeth 100 on the more or less hard grinding cylinders 101-102-103 and 104, rigidly secured by any suitable means in register with the respective wheels 90 to 94 on the inside of a stepped case 106 enclosing the wheels and rigidly, detachably secured on table or case 10 by any suitable means, as for instance, bolts 108. Wheel 94 is made smaller than any of the others so that it will as shaft 24 rotates be rotated at a comparatively slow circumferential

speed to initially break up fuel delivered to it through intake passage 110 in the top 106^a of case 106, such fuel being guided toward the circumference of the wheel by a hub protecting plate 112, secured in position 70 by any suitable means, as, for instance, screws 114. The beaters 98 on this wheel 94 cooperating with the teeth 100 on opposite ring 104 reduces the fuel material initially on top of this wheel and ultimately passing 75 it to particles of, say, a quarter inch in diameter which fall upon the next larger wheel 93. This second wheel 93, rotating at the same angular speed as wheel 94 but at a greater circumferential speed, breaks up this 80 material into a second size of particles of fuel material which pass on to the third wheel 92, in turn rotating at a greater circumferential speed than wheel 93, with the result that still finer particles of fuel material are delivered onto wheel 91 which 85 in cooperation with wheel 90 of the same size operating after it on the material finally reduces the material to the extreme fineness required for powdered fuel firing in which 90 condition the fuel falls into interior recess 86.

The travel of the more and more finely divided fuel material past the wheels described is materially facilitated by air entering the 95 top of the machine through one or more suitable ports provided for the purpose. In the particular case here shown and for illustrative purposes only, the air enters three ports 116 in the top 106^a of the case, the amount of air so admitted being regulated by a multiplicity of valve plates 118 mounted on a common hub manipulatable by a handle 120 selectively lockable in position by a conventional bolt mechanism 122 traveling in a slot 124, preferably, but not necessarily, past a graduated scale 126. Air is drawn through these ports 116 by the suction fan 82-84 driven by shaft 24, as heretofore described. The control of the air admitted to the machine is important because too much air causes an undue coarsening of the product. As the pulverized fuel material drawn by this fan mechanism, just described, enters recess 86 in case 10, it is air driven 100 out of the machine through exit port 128 to the point desired for use. The perforation 87 in plate 85 is important in that air in case 106 below wheel 90 is forced to travel 105 inward toward shaft 24 to get to port 87 and thence out through fan 84, this at the time the beating wheels 90-94 are throwing the heavy material outward in case 106. These opposite motions of the coal and air 110 materially assist separation of the heavy and light particles of coal which is the object of the machine. Experiments show that as opening 87 is increased in size, the finished product is coarsened, the power required to 115 run the machine being correspondingly de-

creased. Disc 85 may be entirely omitted when comparatively coarse product is desired.

Actual experience with this machine demonstrates that horizontally disposed pulverizing wheels 90-94, carried by a central shaft and progressively increasing in size, preferably from top to bottom, as shown, but always with the size of the wheels increasing as the size of the particles of material worked upon decreases, produce highly efficient results not heretofore known in machines of this class.

In order to take care of any coarse material entering the machine through passage 110 which, for any special reason, as for instance its actually being iron, cannot be broken up by the first wheel 94, an outlet passage 130 is provided at one side of the top 20 of the machine leading into a waste chamber of any suitable sort from which such useless material may from time to time be removed. In the particular case here illustrated, this waste chamber takes the form 25 of a pipe elbow closed by a door 134 pivoted at 136 and detachably releasable by removing the pin 138 shown as suspended by a chain 140.

Shaft 24 is rotated by any suitable means 30 outside the structure shown in Figure 4. In the particular case here illustrated, the driving means is an electric motor 142 carried by a conventional standard 144 secured in place by screws or bolts 146 entering cover 25 top 106.

One desirable advantage of the machine of this invention is that the shaft 24 and consequently the grinding wheels 90-94 can be rotated in either direction to produce 40 pulverizing action between beaters 98 and adjacent teeth 100. This is of particular importance in that after one working corner of a beater wears off round, thus impairing the machine, the opposite square corner can 45 be utilized on reversing the rotation of the machine.

The word "wheel" used in the claims is intended to include any sort of rotatable member having or carrying on or adjacent 50 to its circumference one or more material disintegrating device.

The horizontal wheel machine is very economical in power because the wheels at no time have to lift material worked upon 55 as is the case in vertical machines where the wheels have to plow through the material lifting some of it.

In the modified construction of Figure 8, the case and wheel mountings are substantially identical in function at least with the structure of Figure 4. The wheel hub 76-82 of Figure 4 is, however, replaced with another wheel hub 150, having an outwardly inclined inner surface 152 of such an angularity that no dust or dirt can be

held by centrifugal force on this conical surface 152. This wheel hub 150 is provided on its external, conical surface with a multiplicity of steps 154, to each of which is rigidly attached, by means not here shown, 70 an annular beater carrying wheels 156, the solid portions of such wheels being of substantially the same radial width, said wheels, however, increasing progressively in actual diameter as required by the steps 154. (See 75 Fig. 8.) The outside circumferences of these wheels 156 are located inside of a stepped case 158 corresponding to case 106 of Figure 4.

Located intermediate between each pair 80 of wheels 154 are a multiplicity of improved beaters shown in detail in Figures 10 and 11. Each beater is made with a large, relatively heavy head 162 of triangular form, as clearly shown in Figure 10, extending 85 from a hub 164 pivotally journaled upon a post or pin 166, detachably mounted, as shown in Figures 10 and 11 on two adjacent parallel, horizontally disposed wheels 154. Each one of these pins 166 has an enlargement 90 intermediate of its length adapted to take bearing in a recess 170 within the adjacent beater 160 which is larger than the normal perforation 172 through the beater for the reception of the main lower portion 95 of pin 166. The wheel 154 which is above a given beater 160 is provided with a perforation 174 of sufficient diameter so that the entire pin device 166, including the enlargement 168, can be passed upwardly out 100 through this opening or perforation 174.

The clearance of the respective parts is such that pin 166 and adjacent beater 160 can be rocked to the right, as viewed in Figure 10, a sufficient distance to allow the described withdrawal of pin 166 and the consequent release of a given beater 160.

By reference to Figures 9 and 10 of the drawing it will be seen that by placing the outer edges of the beaters 160 substantially flush with the outer peripheral edges of the discs 154, I have provided a construction which prevents the body of material to be pulverized, from passing quickly through the machine under the influence of gravity and the air current. This construction is quite important, since it prevents any great amount of space between the outer edges of these discs and the grinding rings through which the material might pass without being impacted by the beaters. It will also be observed that I have arranged the beating elements wholly above the discs 154 on which they are mounted. In the normal operation 115 of the wheel construction, just described, 120 the entire wheel mechanism 150 is rotated at high speed inside the case with the result that beaters 160 all swing outward under centrifugal force to radial position. The mass of the triangular arm 162 of each 130

beater 160 is sufficient to hold such particular beater in extended position during all material breaking operations for which the machine is designed; but owing to the fact that the beaters are thus extended, only by centrifugal force, any one of them can swing on pivot pin 166 to avoid any obstruction in the path of the beater which obstruction cannot be broken up or otherwise moved by the beater. This construction prevents breakage and damage to the whole machine when solid pieces of iron or other material gets into the stream of material passing through the machine and being broken up by the beater.

In other respects than those described, the modified structure of Figures 8 to 10, inclusive, operates identically with the device of Figures 1 to 7, inclusive.

20 When the breaking member 160 is thrown outward by centrifugal force, viz: moved to the left as shown in Figures 10 and 11, the side 180 of the upper end of pin 166 takes bearing against surface 182 in perforation 174 which throws the side 184 of enlarged member 168 to the left of shoulder 186, Figure 11, and thus prevents accidental movement of the pin upward and consequent accidental release of the breaking member 160.

Having thus described my invention, what I claim as new and desire to secure by Letters Patent is:

1. In a pulverizer, a casing, a vertically disposed rotatable shaft within said casing, a bearing for said shaft, a hub of substantially inverted U-shape in cross section affixed to said shaft extending downwardly around said bearing and terminating in a downwardly and outwardly flared portion at its lower end, a plurality of disintegrating wheels carried by said hub cooperating with said casing to pulverize material supplied to said casing, fan blades carried by said flared portion, and a plate between said wheels and said fan blades cooperating with said casing to form a fan chamber, said plate being apertured near its center whereby an air current produced by said blades draws material inward towards the center of said casing after it has been thrown outward therein by centrifugal force due to rotation of said wheels, said fan chamber having an outlet opening in the side thereof in horizontal alignment with said flared portion of said hub.

2. In a pulverizer, a circular stepped casing the diameters of the stepped portions of which progressively increase towards its lower end, a plurality of superimposed wheels progressively larger in diameter from top to bottom of the group located within said casing and cooperating therewith to pulverize material delivered into the same, a fan chamber beneath said

wheels, a fan within said fan chamber acting to create an air current for drawing pulverized material into said chamber and to force such material from said chamber through a lateral discharge opening therein, and a waste chamber communicating with said casing through a lateral opening in the latter horizontally aligned with the space between the uppermost wheel and the top of the casing.

3. In mechanism of the class described, a pair of separated parallel rotatable wheels, a pivot pin extending through adjacent wheels, a material breaking member swingable on said pivot pin between said wheels, said pin being insertable in perforations in the wheels and breaking member and having an enlargement preventing passage thereof through the breaking member and also preventing removal thereof from securing relation to the breaking member until said pin is moved transversely to a predetermined position.

4. In a pulverizer, a casing having a material inlet opening in the top thereof, a vertically disposed rotatable shaft within said casing, a hub fixed on said shaft, the outer face of said hub being provided with a series of steps, plates seated on said steps and rotatable with the hub, and a plurality of material breaking members secured between adjacent plates.

5. In a pulverizer, a casing having an inner vertical wall of stepped formation, an inlet opening in the top thereof, a vertical shaft in said casing and a plurality of horizontal, vertically spaced apart discs on said shaft progressively increasing in diameter from top to bottom of said shaft, a plurality of beating elements on each disc and arranged in spaced relation about the periphery of each disc, each beating element having a peripheral arcuate face and having vertical sides tapering inwardly from the arcuate face toward the vertical shaft, the curved peripheral face of each beater rotating in a path adjacent the vertical wall of the stepped portion of the casing and said vertical wall having teeth which face in both a clockwise and anti-clockwise rotational direction, and means for rotating the vertical shaft in either clockwise or anti-clockwise direction.

6. In a device of the class described, the combination of a casing, a vertical shaft therein, a plurality of horizontal discs spaced apart, vertically on said shaft, a plurality of beating members and means individual to each of said members for pivotally and detachably mounting them on the periphery of the discs and associated devices actuated by the centrifugal force of the rotating beaters on the disc for locking said beaters from inadvertent detachable movement.

7. In a device of the class described, the combination of a casing, a rotatable vertical shaft therein, a plurality of discs horizontally mounted on said shaft for rotation therewith, a plurality of vertical pivotal pins for detachably and individually connecting the beating elements to the discs, said pins being vertically shiftable to permit the detachment of the beaters from the 10 disc, said beaters, discs and pins being constructed and arranged under the action of the centrifugal force of the beaters to lock said pins from vertical movement.

8. In a device of the class described, the 15 combination of a casing enclosing a vertical, rotatable shaft, a series of discs rotatable with said shaft, a plurality of beaters, means for pivotally mounting the beaters on the disc, means for permitting the free removal 20 of the pivotal means for the beaters, said means being constructed and arranged to be affected by the centrifugal force of the rotating beaters for locking the pivotal means from detachable movement.

25 9. In a device of the class described, the combination of a casing enclosing a vertical rotatable shaft, two discs horizontally disposed and vertically spaced apart on said shaft, a plurality of beaters adapted to be 30 mounted at the periphery of the lower disc and between said discs, said discs having registering perforations, a pivotal pin passing through said perforations, and through a registering bore in the beater, the bore of 35 the beater having a portion of enlarged diameter directly underlying the bore of the superior disc and said pin having enlarged head seating in said bore of enlarged diameter, said bores of the discs and beater and said head being constructed and arranged to permit a portion of the head to underlie a portion of the superior disc under the centrifugal force of the rotating beater whereby to lock the pin from endwise movement.

40 10. In a device of the class described, the combination of a casing, a rotatable vertical shaft therein, two discs horizontally mounted on said discs and spaced apart vertically thereof, said discs having registering bores, 45 a beater adapted to be pivotally mounted between said discs, said beater having a registering bore provided with an enlarged mouth portion, a pivotal pin passing through the bores of the two discs and of the beater, said pin having enlarged head lying in the enlarged bore of the beater and said pin being vertically removable to permit the detachment of said beater and means constructed and arranged to permit outward 50 movement of said pin under the action of the centrifugal force of the rotating beater for locking the pin against endwise movement.

55 11. In a pulverizer, a casing having a material inlet opening at its top, a vertically disposed rotatable shaft within said

casing, a hub comprising an inverted substantially conical shell having its small upper end closed about the shaft and its lower end spaced therefrom and enclosed by the casing, but spaced therefrom to form a 70 chamber, beaters carried by said hub to rotate within said casing, and air propelling vanes mounted on the lower end of said hub to rotate within the chamber to draw the air through past the beating members during their rotation. 75

12. In a pulverizer, a casing, a vertical shaft rotatable within said casing and a grinding ring mounted on the interior of said casing and provided with working surfaces, pulverizing means having disks on said shaft and carrying pulverizing beaters adapted to rotate and co-operate with the working surfaces of the grinding ring, a plate located below said pulverizing means to 80 enclose them and to form a pulverizing chamber above said plate concentrically about said shaft, said plate extending from the outer part of the casing inwardly toward the shaft and terminating short of said shaft 85 to form a discharge opening. 90

13. In a pulverizer, a casing, a vertical shaft rotatable therein, pulverizing means rotatable within said casing and including a plurality of vertically spaced apart 95 imperforate discs having beating elements on their peripheries adapted to rotate closely adjacent the wall of the casing, a plate extending across the bottom of said casing below the pulverizing means to enclose them, 100 said plate having its inner portion spaced from the shaft to form a discharge for the pulverizing means, and an air blower on the shaft beneath the plate for moving the pulverized material from the casing. 105

14. In a pulverizer, the combination of a casing, a vertical, rotatable shaft bearing a vertical series of pulverizing beaters thereon, a material inlet for the top of the casing, a pulverized material discharge for the bottom of the casing, an outlet at the top of said casing in the horizontal plane of the uppermost beater of the series for the discharge of non-pulverizable material. 110

15. In a pulverizer, the combination of a 115 casing having a stepped inner surface, a vertically rotatable shaft within said casing, a material inlet at the top of the casing, a vertical series of rotatable plates on said shaft and increasing in diameter from the top of the series downwardly, said plates having beaters rotatable past the vertical wall portions of the stepped inner wall of the casing, the uppermost vertical wall opposite the top beater having an opening 120 therein to discharge non-pulverizable material. 125

16. In a pulverizer, the combination of a casing, a vertical rotatable shaft having a vertical series of pulverizing beaters there- 130

on, a material inlet at the top of the casing, a plate rotatable with the shaft and located beneath the inlet, and an outlet at the top of the casing on the horizontal level of the 5 uppermost beaters and in their path of travel, for the discharge of non-pulverizable material.

17. In a pulverizer, a casing having an inner circular wall provided with angular projections facing both clockwise and counter-clockwise directions and a vertical shaft having thereon rotatable beaters adapted to rotate close to said projections to pulverize material therebetween and a reversible motor mounted directly on said shaft for rotating the beaters in either direction.

18. In a pulverizer, the combination of a casing, a vertical shaft rotatable therein, a substantially conical hub mounted on said 20 shaft to rotate therewith, pulverizing members rotatable with said shaft, means for feeding material into the top of said casing and for discharging the pulverized material from the bottom of said casing, lubricating 25 means for said shaft, an air blower carried by the lower part of said hub for blowing the pulverized material from the casing, the inner face of said conical hub being outwardly inclined and of such angularity as to 30 prevent dust and material from accumulating thereon under the action of the centrifugal force created by the rotating hub.

19. In a pulverizer, the combination of a casing having a stepped inner surface, 35 which progressively increases in diameter from top to bottom, a series of vertically spaced plates rotatable in the casing, and likewise gradually increasing in diameter, beating elements on the periphery of each 40 plate, each beating element traveling in a path close to the vertical wall of the stepped portions of the casing, and an air blower disposed beneath the last of said series of beaters for drawing air through the beaters.

45 20. In a pulverizer, a casing, a rotatable shaft therein, a beater, means for detachably and pivotally mounting said beater on said shaft whereby said beater is rotated by said shaft, and means for automatically locking the beater against detachment during the rotation of said beater.

21. In a device of the class described, the combination of a casing having a grinding ring on its inner wall provided with working surfaces, a vertical shaft rotatably mounted in said casing and carrying a series of vertically disposed spaced apart discs the outer edges of which lie close to and rotate past the working surfaces of the grinding 55 ring and a plurality of beating elements mounted on the periphery of each disc, said beating elements having their outer beating surfaces flush with the peripheral edges of the disc and adapted, by their rotation close 60 to the working surfaces of the grinding ring,

to cause the pulverization of the material passing through the machine.

22. In a device of the class described, the combination of a casing having an inner surface arranged in stepped formation and gradually increasing in diameter from the top toward the bottom of the casing, the inner vertical walls of said casing having working surfaces thereon, a shaft vertically rotatable in said casing and provided with a plurality of imperforate discs gradually increasing in diameter from top to bottom of the shaft, said discs having a plurality of beaters mounted on the peripheral portions of each disc with the outer edges of the beaters lying substantially flush with the peripheral edges of the discs and the outer peripheral edges of said discs and beaters rotating close to the working surfaces of the casing so as to pulverize the material passing through said casing.

23. In a device of the class described, the combination of a casing having working surfaces on its inner walls, a vertical shaft rotatable in said casing and provided with a plurality of vertically disposed and spaced apart discs and a plurality of beating elements mounted wholly on the upper faces of the peripheral portions of said discs and adapted to co-operate with the working surfaces of said casing to pulverize the material passing through said casing, said discs having their outer edges disposed substantially flush with the outer edges of the imperforate discs and lying adjacent the working surfaces of the casing.

24. In a pulverizer, a casing, a vertical shaft rotatable within the casing, a grinding surface formed in said casing and pulverizing means adapted to co-operate with said grinding surface, said means comprising a disc supported from said shaft and beaters mounted on said disc in position such that their outer faces are disposed adjacent the grinding ring and co-operate therewith to pulverize material passing therebetween, said disc having peripheral portions extending between the beaters adjacent to the grinding surface to direct material being pulverized between the outer faces of the beaters and the grinding surface.

25. In a pulverizer, a casing, a vertical shaft mounted for rotation within the casing, a disc supported by said shaft and extending outwardly therefrom toward the casing, beaters carried by said disc in position so that their outer ends may move adjacent the casing, the peripheral edge of the disc extending between adjacent beaters in line with the outer edges thereof whereby material to be pulverized may not pass between adjacent beaters.

26. In a pulverizer, a casing having an interior peripheral grinding surface, a rotatable shaft arranged within the casing and

- 5 pulvverizing means carried by said shaft in position to swing adjacent said grinding surface to co-operate therewith to pulverize material passing therebetween in a direction parallel to the axis of said shaft, said grinding means including a hub secured to the shaft, an annular disc carried by the hub and beaters carried at the periphery of the disc, the disc being extended, between the 10 beaters to adjacent the grinding surface to prevent the passage of material to be pulverized past the beaters except along a path between the outer surface of the beaters and the grinding surface.
- 15 27. In a pulverizer, a casing, means formed in said casing providing grinding surfaces, a shaft mounted for rotation in the casing, pulverizing means carried by said shaft in position to swing adjacent said surfaces and co-operate therewith to grind material passing therebetween, said pulverizing means including a plurality of discs arranged in spaced relationship, said discs being carried by said shaft, and beaters mounted 20 on said discs in position to co-operate with a said grinding surface to form a pulverizing stage, and means whereby one stage discharges into the next succeeding stage at a point therein spaced within the edge of the 25 disc.
- 30 28. In a pulverizer, a casing, means formed in said casing providing grinding surfaces, a shaft mounted for rotation in the casing, pulverizing means carried by said shaft in position to swing adjacent said surfaces and co-operate therewith to grind material passing therebetween, said pulverizing means including a plurality of discs arranged in spaced relationship, said discs being carried by said shaft, and beaters mounted 35 on said discs in position to co-operate with a said grinding surface to form a pulverizing stage, said casing having means whereby the work material may be discharged from one stage into the succeeding stage at points spaced within the periphery of the disc thereof.
- 40 29. In a pulverizer, a casing, a vertical shaft rotatable within the casing, grinding surfaces formed in said casing and pulverizing means adapted to co-operate with each of said grinding surfaces, each of said means comprising a disc supported from said shaft and beaters mounted on said disc in position 45 such that their outer faces are disposed adjacent the grinding ring and cooperate therewith to form a pulverizing stage, said disc having peripheral portions extending between the beaters to adjacent the co-operating grinding surface to prevent the passage 60 of work material through the stage except along a path between the outer surfaces of the beaters and the grinding surface and said casing having means arranged therein for directing work material discharged from one stage into the next succeeding stage at points spaced inwardly of the periphery thereof.
- 55 30. In a pulverizer, a casing, a vertical shaft rotatable within said casing, a grinding surface arranged on the interior of said casing and providing a working surface, pulverizing means comprising a disc carried by said shaft and pulverizing beaters secured to said disc and adapted to co-operate 70 with the working surface, a plate located beneath said pulverizing means to enclose it and provide a pulverizing chamber above said plate, said plate extending from the casing inwardly to adjacent the shaft and terminating short of the latter to form a discharge opening thereabout, and air propelling vanes mounted for rotation with said shaft and arranged beneath said plate to draw air downwardly past said beaters and 75 through said discharge opening.
- 60 31. In a pulverizer, a casing having an inlet opening in its upper portions, a vertical rotatable shaft arranged within said casing, a hub comprising an inverted substantially conical member having its smaller upper end closed and secured to the shaft and its lower edge spaced from the shaft, a series of spaced annular plates mounted on said hub, increasing in diameter from the 80 top of the series downwardly, said plates having beaters pivotally mounted thereon, said beaters having their outer surfaces flush with the peripheral edges of the discs and adapted upon rotation of the shaft to co-operate with the inner walls of the casing to cause the pulverization of material passing through the machine, and air propelling vanes mounted at the lower outer edge of 85 said hub to rotate therewith to draw air past the beaters during the rotation of the shaft.
- 65 In witness whereof, I have hereunto subscribed my name.

AUBREY J. GRINDLE.
